UNITED STATES PATENT OFFICE.

CHARLES J. LEHN, OF OAK PARK, ILLINOIS.

FURNACE CONTROL.

Application filed September 24, 1923. Serial No. 664,356.

My invention relates to furnace controls, being more especially concerned with the control of the several furnaces constituting a battery, and also of furnaces having automatic fuel stokers. Certain phases of my invention, however, are not necessarily limited to these types.

One object of my invention is a control for a battery of furnaces such that the output rates of the several furnaces are brought from a low to a high rate, or vice versa, in successive order. Thus, certain of the furnaces are operated at a high rate of output—where they operate most efficiently—while others are idle, merely preserving their fires. As the demand on the battery increases, other furnaces are brought to this high output rate in successive order as needed. This is in contradistinction to controls whereby all the several furnaces are operated simultaneously at the same intermediate rate determined by the demand on the battery.

Another object of the invention is a dual control for the regulating means of the individual furnaces of a battery, whereby either the demand on the output of the battery or the condition of the individual furnace controls the rate of the respective furnace. I thus obtain the advantage of being able to regulate the active functioning of a particular furnace by the demand on the battery and at the same time prevent the running of the furnace at an inefficiently high rate by a thermostat responsive to the temperature of flue gases in the furnace.

A further object of my invention is the joint control of a plurality of regulating means for the individual furnaces of a battery.

Many other objects, features and advantages of my invention will appear from the following description and claims, as well as from the accompanying drawings, in which

45 Figure 1 is a front view showing diagrammatically a battery of furnaces provided with the furnace control of my invention;

50 Figure 2 is an enlarged side elevation of one of the furnaces of Figure 1;

55 Figure 3 is a detail view of the control unit of my invention;

Figure 4 is a fragmentary and diagrammatic elevation of one of the stoker control mechanisms; and

65 Figure 5 is a vertical section of one of the thermostats.

Similar characters of reference refer to similar parts throughout the several views.

As shown in Fig. 2, a plurality of furnaces 10^a to 10^e are grouped together to form a battery, the boiler of each furnace supplying steam to a common steam header 11 extending along the rear of the furnaces. Each furnace 10 is provided with an automatic fuel stoker 12, here shown as being of the endless chain type. As shown in Fig. 4, the chain grate 13 passes over a front sprocket 14, the sprocket 14 being driven through a series of reduction gears 15 by a ratchet wheel 16. The pawl 17 which cooperates with the ratchet wheel is pivoted at 18 to an actuating arm 19, one end of which is pivoted to the shaft 20 of the ratchet wheel 16, while the free end of the arm 19 is provided with a slot 21. The arm 19 is oscillated periodically to advance the ratchet wheel 16 by an eccentric rod 22, the upper end of which encircles the large diameter of an eccentric 23 mounted upon a power shaft 23' extending the length of the battery. The stoker thus far described may be of any of the several suitable types now in use, the details of the stoker itself forming no part of my invention.

In lieu of the usual clamping means for securing the free end of the eccentric rod 22 to the arm 19 at one of its adjusted positions, I provide an automatic means for adjusting the leverage of the eccentric rod upon the actuating arm 19, this means comprising a link 24 connecting the pin 25, which pivots the end of the rod 22 in the slot 21, with a diaphragm-actuated lever 26. The lower end of the lever 26 is pivoted to the customary frame of a diaphragm control mechanism 27, the diaphragm 28 of which is connected to the lever 26 adjacent its fixed pivot to provide a relatively long movement for the link 24, as will later be explained. Air under pressure is led by the tube 29 to one side of the diaphragm 28. A tension spring 30 is provided which normally urges the lever 26 to balance the pressure of the air against the diaphragm. This balancing spring tension may be varied by means of a plurality of holes 31 at the upper end of the lever 26. It is clear that an increased air pressure against the diaphragm 28 will swing the pivot pin 25 of the eccentric rod outwardly in the slot 21 so that the reciprocating movement imparted by the eccentric 23 will lessen the number of

- teeth advanced with each reciprocation by the pawl 17, while a lessening of the air pressure against the diaphragm 28 will, conversely, increase the advancing of the 5 ratchet wheel 16, and, consequently, feed new fuel along the chain grate at a faster rate, resulting in a more intense fire, and, consequently, greater steam output from the boiler.
- 10 Air under pressure is supplied to the tube 29 through a vertical branch pipe 32 communicating with a supply pipe 33 extending across the front of the furnaces from an air tank 34. The air pressure in the tank 15 34 may be kept constant by means of a pressure reducing valve 35 in a feed pipe 36 leading from any suitable source of air under pressure.
- 15 From the branch pipe 32 a transverse pipe 37 leads to the rear of each furnace and communicates with a thermostat 38 at the top of the furnace and with a diaphragm mechanism 39. This diaphragm unit, which is similar to the diaphragm mechanism 27 20 associated with each of the stoker controls, opens and closes a damper 40 for controlling the escape of flue gases from the particular furnace to the breeching 41 extending the length of the battery. As shown in Fig. 2, 25 an increase in air pressure against the diaphragm of the unit 39 will lift the lever 42 on its fixed pivot 43, allowing a counter-weight 44 to pull a cable 45 around a sheave 46, the latter being secured to the shaft of 30 the damper 40. Increased pressure in the line 37 thus closes the damper 40, checking the fire of the furnace, while a lessening of the pressure in the line 37 opens the damper to provide more draft for the particular 35 furnace.
- 40 Leading from the respective branch pipes 32 of the several furnaces 10^a—10^e are a plurality of tubes 47^a—47^e, respectively, extending to the control box 48 shown in Fig. 45 3. From the steam header 11 a small steam pressure pipe 49 also extends to the control box 48 communicating with the fluid pressure side of a diaphragm device 50, which works against the pressure of a spring 51 50 to raise the short lever arm of a control lever 52 having a fixed pivot at 53 on a suitable bracket. At the opposite side of the box 48 a bracket 54 provides a guide-way for the free end of the lever 52, a 55 second lever 55 also being pivoted at 56 on the bracket 54 and connected to the free end of the control lever 52 by a link 57. The respective tubes 47^a—47^e lead to terminal stems 58^a—58^e secured in spaced relation to a bracket 59. In that portion of the bracket 59 shown as overhanging these terminals a plurality of valve rods 60^a—60^e are reciprocably mounted so that their heads may contact the open ends of the respective stems 58^a—58^e to close atmospheric relief for the
- several tubes. The upper end of each valve rod 60^a—60^e extends through an aperture in the second lever 55 and is provided thereabove with a nut and lock nut 61. These nuts are so adjusted on the several rods that when the second lever 55 is lifted about its fixed pivot 56, the valve rod 60^a will be lifted from its mating valve seat or terminal stem 58^a and, with continued raising of the lever, the valve rod 60^b will next be 75 raised from its cooperating stem 58^b and so on until finally the rod 60^e is lifted from the terminal 58^e. In this way the tubes 47^a—47^e are relieved to atmosphere in successive order, the number of tubes thus being relieved to atmosphere being dependent upon the steam pressure conveyed to the diaphragm 50. Because of the combination of leverages employed, it will be seen that a very slight fluctuation in the steam pressure 80 against the diaphragm 50 will result in considerable movement of the free end of the second lever 55 which lifts the valves from the valve seats or terminals of the tubes 57^a—57^e.
- 85 When the engine 62, which the steam header 11 is here shown as supplying, is required to be operated at a greater rate, the pressure of steam in the header 11, of course, falls. This slightly lessens the pressure 90 against the diaphragm 50, thus raising the free end of the operating lever 52 and in turn the second lever 55, here shown as just beginning to raise the valve 60^e from its mating terminal 58^e to relieve the tube 47^e. 100 The pressure in the air lines 37 and 29 of the particular furnace 10^e is likewise reduced, allowing the spring 30 to pull against the stoker control diaphragm 28 drawing the eccentric rod 22 toward the pivot of the arm 105 19 to increase the feed of the stoker. At the same time the lessening of the pressure in the line 37 permits the lever 42 of the damper control diaphragm device 39 to swing downwardly, opening the damper 40 to increase 110 the furnace draft.
- 110 It is necessary not only to increase the fire of a particular furnace to its most efficient rate when the demand on the battery as a whole occasions, but also to provide means 115 for regulating the particular furnace so that its fire does not become excessively hot and the furnace operate at more than its most efficient rating, as this would result in a wasting of fuel and likewise endanger the 120 furnace and boilers. For this reason I provide a second control for the regulating of the particular furnace, this second control being responsive to the condition of the particular furnace. As the temperature of the 125 combustion gases of a furnace forms an excellent index by which to determine the efficiency of its operation, I provide the previously mentioned thermostat 38 for each furnace, the thermostat being responsive to 130

the temperature of such combustion gases. As shown in detail in Fig. 5, the thermostat is mounted in the side of a furnace, being supported by a frame 63 having a rearwardly extending boss 64 into which is threaded the outer end of a metal tube 65 which extends inwardly and across the path of the escaping flue gases. At the inner end of the tube 65 a cap 66 is secured which centers a glass rod 67 (or other rod having a coefficient of expansion considerably less than that of the metal of the tube 65). The outer end of the glass rod protrudes through the frame 63 and is engaged by the end of the adjustable screw 68. The screw 68 is supported in a downwardly extending lever 69, the pivot of the lever being provided for in its upper end by a short strip of spring steel 70 clamped on the frame 63. My purpose in providing such a pivot arrangement is to prevent any lost motion for the lever 69. The lower end of the lever 69 is provided with another adjustable screw 71, the end of which acts as a closure for the terminal fitting 72 of an air line 73 which, as shown in Fig. 2, communicates with the rearwardly extending air line 37. A weight 69' is attached to the lower end of the lever 69 and the mass of the weight is spaced vertically from the pivot strip 70 sufficiently so that gravity will tend to swing the lever 69 inwardly at all times keeping a pressure against the glass rod 67. When a particular furnace has been brought to too high a temperature for efficiency, the heat of the escaping gases will expand the metal tube 65 of the thermostat considerably faster than the glass rod 67 expands, allowing the lever 69 to be swung inwardly so that the end of the screw 71 closes the terminal of the air line 73. This, it is obvious, results in an increased pressure on the diaphragm of the control device 39, resulting in a closing of the damper 40 to check the fire. The increased air pressure also actuates the stoker control diaphragm 28 to decrease the stoker speed. When the fire has been sufficiently checked, the thermostat will again relieve the air line 73, opening the draft and increasing the stoker feed.

In order to secure the most advantageous operation and sensitiveness of the control system, a needle valve 74 is provided in each of the branch air lines 32 so that the flow of compressed air into the system of each particular furnace control will cooperate with the rate of relief provided for the apertures of the several relief terminals.

In order to establish a proper balance of pressures as between the stoker control and the damper control, I also provide a needle valve 75 in the air line leading to each damper control diaphragm device 39.

Because of the great sensitiveness of the control device in the box 48 to fluctuations

in the steam pressure, the closing of a particular terminal 58^a—58^b will provide more than merely on and off positions, for, especially when high air pressure is employed in the system, the lifting of a particular valve rod 60^a—60^b will have somewhat the effect of a needle valve during the first few thousandths of an inch of movement, so that intermediate positions of the respective dampers 40 and stoker regulators 75 will be obtained. In this way the control system will quickly bring itself to a balance rather than a frequent alternation between a hot fire and a slow fire in one of the furnaces. 80

I have also shown my control system as including the regulation of a forced draft for each of the furnaces of the battery. As shown in the drawings, each furnace is provided with an individual forced draft by means of a blower 76 driven by an individual steam turbine 77. A steam pipe 78 extends from the steam header 11 beneath the battery of furnaces and supplies each turbine 77 with steam for its operation. In the passage between the common steam line 78 and each individual turbine is inserted a regulating valve 79 controlled by a diaphragm device communicating with the air line system of the respective furnace. Thus, when the air line of a furnace is relieved, due to a falling in the common steam pressure, the regulating valve 79 is permitted to open farther, admitting more steam to the turbine 77, increasing the forced draft. Conversely, when the air pressure in the control system for the respective furnaces is closed, the increased pressure in the line will diminish the steam supply to the turbine and decrease the forced draft. 100

I provide cutoff valves 80—80 in the air pipes of each furnace control system whereby any of the several devices may be rendered inoperative, if desired. When it is desired to make repairs in one of the furnaces, or for other reason to drop it out of active service in the battery, the control for that furnace may be rendered inoperative by closing the valve 81 in the branch pipe 32. 105

Although I have illustrated and described but one embodiment of my invention, it is to be understood, of course, that its application is not thus limited and that many changes may be made without departing from the scope or spirit of my invention. 115

I claim:

1. The combination with a battery of furnaces, of means controlled by fluctuations in the demand on said battery for changing the output of successive furnaces of said battery 125 between operating conditions of low and of high output, said means including regulating means for controlling the respective individual furnaces in response to their temperatures. 130

2. The combination of a plurality of furnaces supplying a common demand, each of said furnaces normally operating at low output, means responsive to said demand for bringing the operation of said several furnaces to higher output in successive order, and means responsive to the temperatures of the individual furnaces for controlling them respectively.
- 10 3. The combination of a plurality of furnaces supplying a common demand, each of said furnaces normally operating at low output, means responsive to said demand for bringing the operation of said several furnaces to a higher output in successive order, and means responsive to the temperatures of said individual furnaces for controlling the output of the respective furnaces.
- 15 4. The combination of a plurality of boiler furnaces furnishing steam to a common supply, fuel feed means for each of said furnaces, a plurality of control means, in association respectively with each of said feed means, for varying in successive order the rates of such fuel feeds in said several furnaces, said control means being responsive to the pressure of said common steam supply, and also to the conditions of the respective individual furnaces.
- 20 5. The combination of a plurality of boiler furnaces furnishing steam to a common supply, fuel feed means for each of said furnaces, a plurality of control means for varying in successive order the rates of such fuel feeds in said several furnaces, said control means being responsive to the pressure of said common steam supply and also to the temperatures of the individual furnaces.
- 25 6. The combination of a plurality of boiler furnaces furnishing steam to a common supply, fuel feed means for each of said furnaces, and means controlled by said common steam supply and by the temperature of the flue gases in each furnace for regulating said fuel feed means.
- 30 7. The combination of a plurality of boiler furnaces furnishing steam to a common supply, regulating means for each of said furnaces, and means controlled either by said common steam supply or the temperature of combustion gases in said furnace for operating said several regulating means in successive order.
- 35 8. The combination with a plurality of furnaces contributing to a common output, of fuel feed regulating devices for each of said furnaces, each such device being controlled in response either to said common output or to the temperature of the respective furnaces.
- 40 9. The combination with a battery of furnaces furnishing a heated article to a common supply, of a fuel feed regulator for each of said furnaces, each said regulator being controlled either by the condition of said supply or by the condition of its associated furnace.
- 45 10. The combination of a plurality of furnaces contributing to a common supply, fuel feed means for each of said furnaces, said feed means being controlled by either the temperature of their respective said furnaces or said common supply.
- 50 11. The combination with a plurality of boiler furnaces furnishing steam for a common supply, of fuel feed regulating means for each of said furnaces, said regulating means being controlled either by said common steam supply or by the temperature of flue gases in the respective furnaces.
- 55 12. The combination of a plurality of boiler furnaces furnishing steam to a common supply, individual regulating means for each of said furnaces, a fluid pressure line for each of said regulating means, a diaphragm in each of said lines for varying the respective said regulating means, a control valve in each of said lines responsive to said common steam supply, and a second control valve in each of said lines responsive to the temperature of flue gases in the respective furnaces.
- 60 13. The combination with a battery of furnaces, each of said furnaces contributing to a joint output, individual diaphragm operated means associated with each of said furnaces for regulating the fire in such respective furnace, fluid under pressure for actuating said diaphragm, a pair of control valves communicating with each of said diaphragms for controlling such diaphragm, one of said pair being responsive to the temperature of the said respective furnace and the other of said pair being responsive to said joint output.
- 65 14. In combination with a battery of furnaces, each of which contributes to a joint output, individual diaphragm-operated means associated with each of said furnaces for regulating the fuel combustion in such respective furnace, a fluid pressure line for operating each said diaphragm, a source of fluid under pressure for supplying said line, and relief means for each said pressure line, each said means being responsive to either said joint output or to the temperature of the respective furnaces.
- 70 15. In combination with a battery of boiler furnaces for supplying a common steam demand, a fuel stoker for each of said furnaces, a fluid pressure operated regulator for each said stoker, two valves for each said regulator, either of which valves controls such fluid pressure of said regulator, one of said two valves being responsive to the temperature of combustion gases in the respective furnace while the other of said two valves is responsive to said common demand.

16. The combination of a plurality of furnaces for a common supply, individual blowers for each of said furnaces adapted to supply forced draft thereto, separate driving means for each of said blowers, and a regulating device for each of said furnaces, said regulating devices being controlled by

the temperature of their respective furnaces and by said common supply and being adapted to control the operation of said 10 blower driving means.

In witness whereof, I hereunto subscribe my name this 12th day of September, 1923.

CHARLES J. LEHN.
